UNITED STATES PATENT OFFICE.

JOHN ARTHUR HIRST AND PERCY SMITH BROOK, OF CHESTER, ENGLAND.

SWITCH GEAR FOR CONTROLLING ELECTRIC MOTORS.

Application filed September 17, 1920. Serial No. 410,976.

To all whom it may concern:

Be it known that we, JOHN ARTHUR HIRST and PERCY SMITH BROOK, subjects of the King of Great Britain, residing in the city

5 and county of Chester, England, have invented certain new and useful Improvements in and Relating to Switch Gears for Controlling Electric Motors, of which the following is a specification.

10 This invention has reference to switch gear for controlling electric motors of that type in which the operating handle has two movements, one of which closes a control switch and the other of which operates the

15 main gear, and has reference to a form of combined main operating and control-switch actuating handle of the angular reciprocating type adapted to move the gear by successive angular steps in the one direction from

20 the off to the on position and from the latter to the off position, the arrangement being such that, if the gear be left in an intermediate position the said control switch is opened and the gear disconnected from the

25 supply main, and such that the forward movement of the handle is arrested when the gear is in the full on position; the invention also relates to the construction arrangement and connections of a suitable

30 form of drum-type electric motor starter, particularly adapted for operation by a handle of the type described by which the angular movement imparted, step by step, to the drum is always in the same direction.

35 In the drawings: Fig. 1 is an elevation with the front plate removed; Fig. 2 is a corresponding side elevation in medial section; Fig. 3 is a fragmentary plan view; Fig. 4 is a side elevation partly in section; Fig. 5 is a front elevation with the ratchet removed.

40 Figs. 6 and 7 are views similar to Figs. 1 and 2; Figs. 8 8^A and 9 9^A are explanatory diagrams. Figs. 10 and 11 are diagrams of a modification.45 Fig. 12 is an elevation of a drum controller, control switch and handle; Fig. 13 is a fragmentary section of the end of the drum; Figs. 13^A, 13^B are detail views of the fixed contacts; Fig. 14 is a perspective view, more or less diagrammatic, of the general

arrangement of the gear; and Fig. 15 is a diagram of connections.

Referring in the first instance to Figs. 1 and 2 and 14:

55 1 is the fixed part of the handle casing which is usually attached to the side of the iron-clad case A (see Fig. 12) in which the gearing is enclosed: 1^a is a cylindrical extension which forms a sleeve mounted 60 so as to rotate about the casing; the handle spindle 2 is pivotally mounted in bearings 1^b and 1^c in the sleeve 1^a, and the sleeve 1^a, spindle 2 and external handle 2^a attached thereto are together angularly movable relatively to the fixed part of the casing, and about the axis of the latter. The handle and spindle are located axially by the pinned washer 2^b.65 2 is a short hollow shaft journaled in the fixed part of the casing, which shaft is adapted to operate the main switch gear, say by the engagement of the claw coupling part 3^a with the rotating part of the switch gear. On the shaft 3 are keyed a ratchet 70 3^b and an indicator 3^c bearing the words "full-on", which words when the gear is in its full-on position, come opposite a window 1^d in the casing 1. A pawl 4 adapted to engage the ratchet 3^b is pivoted on the bracket 75 2^e carried from and rotatable with the rotatable sleeve 1^a of the casing, and to-and-fro movement of the handle and sleeve 1^a impart a step by step movement to the shaft 3. 8085 5 is an axially movable plunger fitted within the hollow shaft 3 and the insulated spherical end 5^a of which is adapted to actuate a control switch in any convenient manner, say by means of an axially movable shaft within the rotatable part of the main switch gear. The plunger 5 has a head 5^b which is adapted to be moved by the angular movement of the handle spindle 2 about its own axis, say by means of a cam piece 2^d 85 fixed on the spindle 2, or in any other suitable manner.90 In the arrangement illustrated the ratchet 3^b has eight teeth, and the limited angular movement of the handle and sleeve about 100 the axis of the casing is somewhat greater than one eighth of a revolution. To-and-fro

movement of the handle about the casing axis therefore, by means of the pawl 4, imparts a step by step rotational movement to the shaft 3 which is transmitted to the gear 5 to be operated by the claw coupling 3^a.

The handle is, as stated, also capable of limited angular movement about its own axis; the spring 2^a normally turns the handle about its own axis to the position in 10 which the cam is clear of the head 5^b of the plunger 5, which latter, or the axially movable shaft which it operates is controlled by a spring which presses it axially to the right. When the gear is operated, it is necessary for the operator first to turn the handle about its own axis and so close the control switch, and then to oscillate the handle about the axis of the casing. Oscillation about the axis of the casing with- 20 out first having turned the handle about its own axis to operate the control switch, merely rotates the gear without closing the main circuit; and if the turning of the handle about its axis and the closing of the 25 control switch is effected only after the first step of the main gear has been passed, the control switch is not effective in closing the main circuit.

When the indicator 3^c shows that the 30 gear has been turned into its full-on position, the handle is released and the normal running position is maintained. A further step breaks the main circuit and returns the gear to the off position in which it is ready 35 to be again operated.

It is desirable when the gear has been moved to the full-on position to arrest the forward movement of the handle 2^a about the casing axis, and this may be effected by 40 electrically controlled locking means, or by mechanically controlled locking means. Figs. 4 and 5 illustrate suitable electrically controlled means.

According to one modification of the invention the handle is arrested when the full-on position is reached by means of an electro-magnetically controlled detent lever which engages with a toothed wheel mounted on a part rotated by the handle, and 50 which, when the appropriate angular position is reached is caused by the energizing of an electro-magnet to hold the said wheel against rotation; the said magnet being energized when the said position is reached, 55 by the action of the switch gear in closing contacts arranged in a suitable energizing circuit. The arrangement in the device illustrated by way of example, is as follows:—

60 6 is a toothed wheel which may be mounted on the shaft 3 or the part of the gear rotated by the said shaft; for instance it may be mounted as shown in Fig. 12, on the drum of a drum type motor starter driven by the shaft 3. The wheel 6, when

direct-coupled to the shaft 3 has the same number of teeth as there are on the ratchet 3^b; 7 is a detent lever pivoted at 7^a controlled by a spring 7^b and having a roller 7^c which engages the spaces between the 70 teeth of the wheel 6 and, by spring pressure on the roller is adapted to hold the switch gear in the successive positions into which it is turned by the handle gear. The detent lever is provided with an armature 7^d which 75 when a suitable electro-magnet 7^e is energized is pulled over and retains the lever in its engaging position. The switch gear is provided with contacts which are closed when the gear is in the full-on position, and 80 the closing of which energizes the winding 7^f of the magnet 7^e. For instance, the contacts 7^g and 7^h (Fig. 15) are closed when the gear is in full-on position and this connects the coil 7^f of the magnet 7^e in series, with cer- 85 tain other energizing coils in a control circuit across the mains. The handle 2^a is thus held fixed until the control circuit is opened by the usual press button provided for the purpose, or until the operation of the no- 90 volt or overload devices.

A mode of mechanically arresting the forward movement of the handle 2^a when the gear has been moved by successive steps to the full-on position is shown in Figs. 6 95 to 11.

According to this modification of the invention the surface of the tooth of the ratchet operated by the handle-driven pawl on which the said pawl rests when the full- 100 on position has been reached, is made either higher or lower than the corresponding surfaces of the other teeth with the result that the pawl, when this stroke is being made, occupies a different angular position in relation to its pivot from that occupied when making the other strokes, and a stop is provided which engages and arrests the pawl before it completes this stroke; said stop being clear of the pawl whilst it is 110 making the other strokes.

In the arrangement illustrated in Figs. 6, 7, 8 and 9 the space 8 of the ratchet 3^b is made less in depth than the other spaces, 115 so that after having made the stroke shown in full lines Fig. 8, which may turn the gear into its full-on position, the pawl 9 is, during the next stroke (the commencement of which is shown in chain dotted lines Fig. 8, and the end of which is shown in full lines Fig. 9) held sufficiently high by the tooth 8^a to ensure, before the stroke is completed, the engagement of the locking piece 9^a with the fixed stop 10 carried from the 120 fixed part of the handle casing 1. The ar- resting of the forward movement before the completion of the stroke indicates to the operator that the gear is in its full-on position which fact is also indicated by the in- 125 dicator 3^c coming opposite the window. The 130

half stroke of the gear completed before the handle is arrested may be used to turn the gear into the full-on position, or the latter position may be reached as described 5 by the last full stroke, the half stroke not altering the gear connections. On moving the handle back the next half stroke will be made, and this turns the gear into the position for starting. The tooth 8^a may 10 be made half the pitch of the other teeth, and if desired the next tooth 8^b in succession may be made half pitch also, so as to facilitate dividing when cutting.

In the modification illustrated in Figs. 15 10 and 11 the space 8' is cut more deeply than the other spaces, when therefore the forward stroke is being made, during which the pawl 9 rests on the tooth 8^a, the engaging part of the pawl is definitely arrested, before the stroke is completed, by the fixed stop 10'. The construction and action is similar to that described in connection with Figs. 6, 7, 8 and 9, except that the pawl is arrested in the locking stroke 20 because it is allowed by the deep space to take a position nearer the axis of rotation than that taken during the other strokes, instead of being held, during the locking stroke, further away from the said axis, by 25 the shallow space, as in the modification first described.

All the teeth including those opposite shallow or deep spaces may, in either of the modifications described, be made of equal 35 pitch if the pawl movement be made, say, slightly more than one and a half times the pitch of the teeth and the portion of the locking stroke made before arrest is more than three quarters of the full stroke; 40 this is shown in Figs. 8^a and 9^a in which case it will be seen that after making three quarters of full stroke shown in full lines, the pawl will be moved back to the position shown in chain dotted lines in which it 45 engages the next tooth edge.

The construction of locking arrangement may, within the invention be modified in other ways; for instance, the shallow or deep spaces may be cut in an auxiliary 50 ratchet, which auxiliary ratchet may be operated by and cause the locking of the main pawl, or an auxiliary pawl may be fitted.

The handle mechanism comprising a handle and spindle capable of reciprocating 55 angular movement about the main axis to operate the main gear, and of limited rotary movement about its own axis, to operate a control switch, may be employed with or without any of the locking devices 60 described, to operate any type of switch gear to which a step-by-step movement, always in the same direction, has to be imparted. It may be applied for instance to switch gear of the kind described in the 65 Specification to Letters Patent No. 118324,

Great Britain, 1920, granted to us. It is however specially applicable to a drum type motor starter, the contacts of which are so arranged that it is moved from the full-on position to the off position by angular movement in the same direction as that by which it was moved from the off position to the full-on position, that is to say a drum, the direction of motion of which does not need to be reversed to turn it from the full-on 70 to the off position.

A drum with connections so arranged is illustrated in Figs. 12 to 15.

The construction and operation will be best understood by describing first the diagrammatic view Fig. 14, and the diagram of connections Fig. 15.

B is a handle mechanism which may be of any type adapted to operate the main gear with a step by step movement, which 80 is constructed as above described in connection with Figs. 1 to 11.

C is a drum preferably mounted co-axially with the shaft 3 operated by the handle as described, and provided with a central 90 axially movable shaft 5^c to which axial movement, in opposition to a spring, is imparted by the plunger shaft 5 (see Fig. 13).

The handle and its casing and mechanism are completely insulated from the drum, 95 the control switch and the live contacts. The shaft 5^c is adapted by axial movement to operate a control switch D.

11, 12, 13, 14, 15, 16 and 17 are fixed contacts connected to the sectionally divided 100 resistance R adapted to be put in series with the armature E of the motor to be controlled, and 11', 12', 13', 14', 15', 16' and 17' are contacts connected together and mounted on the drum, and as the latter is rotated 105 step-by-step it successively cuts out the sections of the resistance and finally, in its full-on position, it short circuits the resistance R by connecting the main contacts 11 and 12.

The mains P and N are connected respectively to the armature E and to the contact 11 through double pole isolating switches 18 and circuit breakers 19, the latter being of the electro-magnetic type held on by solenoids 19^a connected in the energizing circuit 20, and being provided with overload coils 19^b which when they carry excess current, open switches 19^c in the energizing circuit 20. Switches 21, operated by "stop" buttons 120 located in suitable positions about the machinery driven by the motor, are fitted in the energizing circuit 20.

When a shunt resistance is fitted to the motor for speed regulation, the regulator of 125 the shunt resistance 22 is fitted with a switch 22^a in the energizing circuit, which switch is closed only when the resistance is all cut out.

When it is desired to "inch" the motor 130

with all the armature resistance R in circuit, inching switches 23 are fitted, and a branch energizing circuit 20' is carried through fixed contacts 23^a and 23^b to the inching switches; a contact 23' on the drum connects 23^a and 23^b when, and only when the drum is in the off position, so that in this position of the drum the circuit breakers can be closed by closing one of the inching 10 switches.

When the drum is, by means of the handle turned into the first running position, and the handle is turned and the control switch D is closed, the energizing circuit is completed as follows:—

From the negative main through the solenoids 19^a, the stop switches 21, the overload switches 19^c, the shunt controller switch 22^a, the control switch D, contact d¹ to the drum 20 main contacts, thence through the contacts 24 and the contact 24' which make contact, in the first running position only, to the positive main. The circuit breakers are thus closed, and in the second and subsequent 25 running positions the control switch D connects the energizing circuit to the positive main through the drum contacts, the contact 11 and the wire 24'. Should the handle be released in any of the running positions 30 except the full-on position the control switch D is opened and the energizing circuit broken, whereupon the circuit breakers open. When the drum is turned to the full-on position, a contact 7^c on the drum makes 35 contact with a fixed contact 7^b, and the wire 7^k short circuits the control switch D and the shunt regulator switch 22^a when one is fitted, thus permitting the handle to be released and the control switch to be opened, 40 the shunt regulator to be operated and the switch 22^a to be opened without breaking the energizing circuit.

When an electro-magnetic detent such as 7 is used to lock the gear in the full-on 45 position, the winding 7^f of the magnet 7^e is connected in series with the wire 7^k, so that in the full-on position the detent 7 locks the switch gear as described.

The motor is disconnected from the mains 50 by opening one of the stop button switches, after which the gear is turned by the operation of the handle to the off position in which position it is ready for the next operation.

55 Figs. 12 and 13 show a suitable construction of drum type starter. A is an iron-clad enclosing casing, B a handle of the type described; C the drum carried in the bearings c¹ and rotated by the hollow shaft 3 of the 60 handle mechanism, the claw coupling 3^a engaging with a suitable coupling c² on the drum. The drum is fitted with a concentric axially movable shaft 5^e which is actuated by the insulating end 5^a of the plunger shaft 65 5, which in turn is operated by the turning

of the handle about its axis as described. The shaft 5^e by axial movement operates the control switch D which is normally maintained open by the spring d³, and which when closed, connects the contacts d¹ and d² 70 (see Figs. 12 and 14).

The drum carries the contacts 11' to 17', 23', 24, and 7^c, all as described above, and the corresponding fixed contacts 11 to 17, 23, 24^a and 7^b are carried from a suitable 75 base plate. The drum also carries the toothed wheel 6 with which the electro-magnetically operated detent lever 7 engages; the pivot of the lever 7 and the magnet 7^e are carried from the base plate.

130 The fixed contacts are of the elastic yielding and renewable type and are constructed as shown in Figs. 13^A and 13^B.

The bracket 25 of pressed sheet metal is bolted to the base by the terminal studs 25^a, 85 and carries the pivot pin 26 of the finger 27, which is also of pressed sheet metal. The bracket 25, the bent plate 28, the laminated strip 34 and a covering plate 35 are riveted together and form an integral structure 90 which is adapted to be secured to the base plate by the terminal screws 25^a.

The contact 33 is detachably secured to the finger 27 by means of a stud 33^a, the head 33^c of which is square in plan, and of 95 dovetailed shape in profile, and fits a dovetailed recess in the contact 33 so that when the nut 33^b is tightly screwed up with an intervening spring washer the contact 33 is rigidly secured in place on the finger; the 100 screw 33^a is preferably turned from a bar of square section which enables the head to be formed as described; the head cannot rotate in the contact and the contact is prevented from rotating by the flange of the 105 finger 27 so that the nut 33^b can be easily screwed up.

The finger 27 is slotted at 27^a and through this slot extends a screw pin 30 carried from the fixed bent plate 28, and the spring 31 is 110 interposed between the nut 32 and the washer 32^a which latter rests against the finger 27; the spring 31 therefore elastically presses the contact 33 on to the drum surface.

When the contact 33 is worn by the amount represented in double cross hatching (Fig. 13^b) further movement of the finger and contact towards the drum is arrested by the fixed plate 28, but throughout 115 any wear which may take place up to this limit constant elastic pressure is ensured by the adjustment of the nut 32.

29 is a spring secured to the fixed plate 28 by the pin 30; this spring, by pressing 120 against the flats of the nut 32, retains the latter in its adjusted position.

The laminated strip 34 makes electrical contact with the finger by means of the bolt 34^a and interposed spring washer.

- 26^a is a distance ferrule surrounding the pin 26 and extending between the side cheeks of the finger 27 which latter fit between the side cheeks 25^b of the bracket 25.
- 5 The drum, the circuit breakers, the circuit isolating switches and other live parts of the gear are enclosed in the casing A and the door of the casing is usually fitted with a switch *a* (see Figs. 14 and 15) inserted in
- 10 the energizing circuit 20 so that this circuit can be completed only when the door is closed, but of course this switch and such switches as the inching switches, the inching contacts 23', 23^a and 23^b, and the shunt resistance switch 22^a are not essential to the working of the gear.
- 15 Having now fully described my invention I declare that what I claim and desire to secure by Letters Patent is:—
- 20 1. In an improved handle mechanism for operating switch gear; in combination a ratchet mounted on a shaft connected to the main switch gear, a part capable of limited angular movement about the axis of the
- 25 ratchet, a handle spindle mounted in bearings in said part so as to be capable of being turned about its axis, a control switch, an axially movable part adapted to operate the control switch, and to which part axial
- 30 movement is imparted by the said turning movement of the handle, and means for automatically locking the movement of the shaft which operates the switch gear when the full on position is reached; substantially
- 35 as described.
2. In a handle mechanism for operating switch gear, in combination:—a two part casing comprising a fixed casing part and a movable casing part, a hollow shaft mount-
- ed in the said fixed casing part, main switch 40 gear connected to said shaft, a ratchet keyed on said hollow shaft; an axially movable shaft mounted in the hollow shaft; a control switch actuated by said axially movable shaft, said movable casing part being 45 mounted so as to be capable of axial movement about the centre of the hollow shaft; a handle the spindle of which is mounted in diametrically arranged bearings in the said movable casing a pawl carried from a 50 bracket in the said movable part of the casing adapted to operate the ratchet and a cam carried by the handle spindle and adapted, when the latter is turned about its axis to operate the axially movable shaft; 55 substantially as described.
3. In a handle mechanism constructed in accordance with claim 1, the provision of an inter-tooth space on the ratchet of depth unequal to that of the other inter tooth 60 spaces thereon, spaces, and a pawl adapted when it engages the said unequal space to be moved about its axis into a position in which it engages with a fixed stop and arrests the forward movement of the handle; 65 substantially as described.
- In testimony whereof we affix our signatures in presence of two witnesses.
